(57) **CLAIM**

The ornamental design for an instrument panel for a motor vehicle as shown and described.

DESCRIPTION

FIG. 1 is a first perspective view of an instrument panel for a motor vehicle showing our new design;

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view.

The claimed design is shown in full contrast that indicates claimed areas. Half-tone shading indicates areas of unclaimed environmental structure. The broken lines are included as boundary lines and form no part of the claimed design.
